UNITED STATES PATENT OFFICE.

MAXIMILIAN MAYER, OF ORANGE, NEW JERSEY.

COMBINED SPITTOON AND ASH-RECEIVER.

No. 923,192.

Specification of Letters Patent.

Patented June 1, 1909.

Application filed January 13, 1908. Serial No. 410,476.

To all whom it may concern:

Be it known that I, MAXIMILIAN MAYER, a citizen of the United States, and a resident of Orange, in the county of Essex and State of New Jersey, have invented certain new and useful Improvements in Combination Spittoons and Ash-receivers, of which the following is a specification, reference being had to the accompanying drawings, which form part of the same.

My invention relates to a device in which articles of convenience for smokers, &c., of tobacco, are brought together in convenient form, especially adapted for use in halls, restaurants, lodge rooms, card rooms, &c.

In the drawings Figure 1, is a perspective view, partly in section, of an example of my invention; Fig. 2 is a perspective view, partly in section, with the top broken away, of another example of my invention; Fig. 3 is a top view of an ash receiver cover such as may be used with my invention.

In the example of my invention shown in Fig. 1, a stand, 11, of suitable weight is provided, which is adapted to take in a spit box, as the spittoon, 12, having a cover, 13, with a central opening. On one side of this stand, a support, 14, is provided, which has a sleeve, 31, to which the lower end of a tube, 15, is to be secured. This sleeve, 31, may be formed as part of the support, 14, or it may be a separate part brazed or otherwise secured to the part, 14. In this example of my invention the stem, 15, is in the form of a pipe, or tube, and is provided with a discharging end, 17, which is slightly bent toward the spittoon, so that ashes, &c., from the ash receiver, 16, may pass downward and be discharged into the spittoon or cuspidor below. In this example of my invention, the ash receiver, 16, is provided with a funnel-shape or flaring bottom, whereby it is so formed that the ashes, &c., thrown into it will pass directly into the tubular stem, 15, and from that into the receptacle below.

If desired, when an ash receiver, such as 16, is used with my invention, with a tubular stem, as 15, the ash receiver may be provided with an interior vessel, such as is shown at 23, in Fig. 2, into which the ashes are first thrown, and this vessel can be readily taken out and emptied or cleaned whenever necessary.

In Fig. 2, another example of my invention is shown. In this, 24, is a spittoon, hav-

ing a cover, 25, and provided with a central stem, 26, which may be cast or formed as part of the spittoon bowl itself, or there may be a supporting part, 27, in the bottom of the bowl to which the stem, 26, may be secured in any suitable manner. The curved end, 17, of the pipe or tube, 15, is supported in a sleeve, 28, which is slotted to take in a stud, 30, on the stem, 26, similar to a bayonet joint connection.

When desired, a cover part with a central opening, as 18, shown in top view in Fig. 3, which is adapted to be used with my invention, is shown placed on the ash receiver, 16. On this form of cover, several cigar rests, 19, 19, are provided, and this cover, 18, may be secured to a lip, 20, on one side of an ash receiver, as 16. A cigar cutter, as 32, conveniently attached to the support, 21, may also be provided, and this support, 21, may terminate in a screw end, passing through the cover, 18, and lip, 20, and holding the cover and ash receiver securely to each other. Of course, if desired, instead of the cigar cutter, 32, any other suitable device may be attached, as for instance, a lamp.

The stem, 15, may be made of any suitable length, so as to be convenient for the use of persons in standing or sitting positions. When the device is placed in card rooms, lodge rooms, restaurants, and other places where seating conveniences are provided, the stems may be shorter than when my device is to be used in hotel lobbies and other places where no seating conveniences are placed.

It will be seen that this invention relates to spittoons such as are usually placed upon the floor, and as these have been heretofore utilized they have almost always been placed in locations where they are readily pushed under tables, chairs, &c., so that it has not been only very difficult to find them but also inconvenient to get at them for use. By my invention a device is provided which not only indicates the location of the spittoon, but which also prevents placing it in such a position as to make it difficult or inconvenient to get at it for use.

It will be found that by the use of my invention, the carpets, mats, floors, &c., are kept in a much cleaner and neater condition than when cuspidors or spittoons only are provided. It is frequently difficult to cast ashes into a vessel resting directly on the floor, and often such vessels are placed between the feet of the people, and under ta-

bles where it is difficult to see them or to get at them conveniently. With my invention they can be easily seen and readily used for ashes, stumps of cigars, broken matches, &c.

5 I have in the foregoing specification described the present invention as it is illustrated in the accompanying drawings, and such is a preferred construction. I, however, desire it to be distinctly understood 10 that the present invention is not limited to the details of construction which have been set forth, as it is obvious that many changes might suggest themselves to the skilled mechanic without departing from the spirit 15 and scope of my invention.

I do not herein make claim to a solid rod or stem to support an ash receiver, or to an ash receiver suitably mounted on such solid stem, but such subject matter is included in 20 the scope of my original application, and is to be the subject of a division.

Having thus described my invention, what I claim as new and desire to secure by Letters Patent, is:

25 1. As a new article of manufacture, an ash receiver with a funnel-like bottom, a tubular support for the same connected thereto and adapted to sustain it at a convenient height above the floor, a receptacle 30 adapted to rest near or upon the floor connected to such tubular support and adapted to receive the ashes from the ash receiver through such tubular support, in combination with a cover for the ash receiver having 35 a depressed central portion with an opening therein and rests for cigars near its edge, substantially as described and shown.

2. As a new article of manufacture, an ash receiver having a funnel-like opening 40 at its lower end, and a hollow stem con-

nected therewith adapted to support such ash receiver at a convenient height above the floor, in combination with a receptacle adapted to rest upon or near the floor and to hold such hollow stem in position and receive the ashes discharged through the same, substantially as described and shown. 45

3. As a new article of manufacture, an ash receiver having a funnel-like opening at its lower part, a receptacle adapted to rest upon or near the floor, in combination with a hollow vertical stem held in place by such receptacle and adapted to support the ash receiver at a convenient height above the floor and to convey the ashes from the ash 55 receiver to the receptacle, substantially as described and shown.

4. A receptacle adapted to rest on or near the floor, having a hollow vertical handle connected therewith, in combination with an ash receiver having a funnel-like lower portion connected to such hollow handle at a convenient point above the floor, and adapted to discharge the ashes through the same into the receptacle, substantially as de- 65 scribed and shown.

5. A receptacle adapted to rest on or near the floor, and an ash receiver having a funnel-like lower part, in combination with a hollow stem supported by such receptacle 70 and adapted to sustain the ash receiver at a convenient height above the floor and to receive the ashes therefrom and discharge the same into the receptacle, substantially as described and shown.

MAXIMILIAN MAYER.
